UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,846**, dated September 2, 1873; application filed August 9, 1873.
[Term of Patent $3\frac{1}{2}$ years.]

D.

To all whom it may concern:

Be it known that I, FREDERICK WINK, of the city and county of Philadelphia, State of Pennsylvania, have invented a Design for Shawl-Pattern, of which the following is a specification:

My design for a shawl-pattern is clearly illustrated by the figure in the accompanying drawing, the remainder being merely a repetition of that which appears.

The design consists in the peculiar arrangement shown, of a series of wide and narrow parallel stripes, bars, or ribs of different shades

or colors, the grouping being such as to form the main stripes A, B, and C.

Irrespective of the colors employed, I claim—

The design for a shawl-pattern, as represented in and by the accompanying drawing.

In testimony whereof I have signed my name to this specification in the presence of two subscribing witnesses.

FRED. WINK.
